DRILLING MACHINE

Eric J. Hirvonen, Worcester, Mass., assignor to
 Leland-Gifford Company, Worcester, Mass., a
 corporation of Massachusetts

Application January 18, 1933, Serial No. 652,316

22 Claims. (CL 77—32)

This invention relates to machine tools and especially to drilling machines wherein the cutter is moved into and out of engagement with the work by hydraulic mechanism.

The invention particularly relates to machine tools wherein a plurality of hydraulically advanced and retracted cutters operate on the work along lines that contact or are so close together at some point that damage to the cutters and to the machines might result if two cutters were allowed to come into contact. Such a situation can exist in machines designed for the simultaneous drilling of lubricating or oil passages in the crank shafts of internal combustion engines, with which type of machine this invention is particularly concerned. The crank shaft of an automobile engine, for instance, is quite commonly supplied with oil under pressure at the bearing portions thereof and the oil is conveyed through oil passages in the crank shaft from an intermediate bearing portion into the connecting rod portions, or throws, of the shaft on opposite sides of the bearing, the oil passages having a common opening at the surface of the bearing and separately extended at a divergent angle into and opening at the surface of a crank throw. If the oil passages are automatically drilled simultaneously it is possible for the two drills to come into contact with each other at or near the surface of the bearing portion of the shaft, thereby resulting in damage at least to the drills and possible damage to the crank shaft and to the drilling mechanisms.

An object of the present invention is the provision of a machine tool, as a crank shaft drilling machine, having two drilling mechanisms which advance the drills into the work along convergent lines and mechanisms for preventing interference between the cutters or drills.

The present invention embodies two of the drilling units described and claimed in my co-pending application Serial No. 636,855, filed October 8, 1932, each unit having drill rotating means and hydraulic means to advance the drill automatically to successively advanced positions in the work with alternate retracting movements to an intermediate retracted position followed by a final retracting movement to a final fully retracted position where the mechanism is held against further advance of the drill until again restarted on another cycle of operations.

It is a further object of the present invention to provide a combination of two such units arranged to advance their respective drills along lines that converge, with hydraulic control mechanism so arranged that each unit can drill its full length of hole without interference between the drills of the units.

Another object of the invention is the combination of two of the above described drilling units

set to advance their respective drills along convergent lines and interference-preventing hydraulic control mechanism so arranged that the drill that arrives first in the interfering-position is permitted to continue to advance until it is 5 retracted by its mechanism, while the drill of the other unit is prevented from advancing, the control mechanism being so arranged that when the unit that reaches interfering-position first and continues its advance retracts, the other unit 10 advances and holds the first unit against advance, if the mechanism associated therewith is so set as to require further advance thereof.

A further object is generally to improve the construction and operation of hydraulically actuated machine tools.

Fig. 1 is a plan view of a crank shaft drilling machine embodying the present invention.

Fig. 2 is a side elevation of the machine of Fig. 1.

Fig. 3 is an enlarged side elevation of one of the drill units of Fig. 1.

Fig. 4 is a diagrammatic representation of the hydraulic control mechanism for the drill units.

Fig. 5 is a sectional view of a bearing portion 25 of a crank shaft and illustrating the manner in which the drills are advanced into the shaft and the manner in which interference between the drills can take place.

The machine embodying the present invention 30 includes a flat horizontal table 10 on which the similar drill units A, B, and C, D, are supported in such manner that their angular relation with each other and their distance from the work can be changed as desired. The table is supported 35 on a pedestal 12 which preferably is hollow and contains the hydraulic pump and other associated parts of the hydraulic system. The machine is herein illustrated as arranged to drill oil holes in a crank shaft 14 which is here shown 40 as having the two end bearings 16 and the center bearing 18 with the crank throws 20 and 22 on opposite sides of the center bearing and the crank throws 24 adjacent the end bearings. The crank shaft herein illustrated is designed for a four 45 cylinder or, it may be, an eight cylinder, V-type engine. The crank shaft is suitably supported on blocks 26 and is held releasably thereon by clamping levers 28 and the operating levers 30 therefor. Oil passages 32 are drilled from the 50 middle of the bearing faces of the end bearings 16 through the crank shaft to the middle of the bearing faces of the end crank throws 24. Other oil passages 34 and 36 are drilled from the middle bearing faces of the middle crank throws 20 and 55 22 into the middle of the bearing face of the center bearing 18, the oil passages 34 and 36 being convergent and merging into one another at or near the face of the bearing 18.

The invention is particularly concerned with 60

drilling of the passages 34 and 36 and the drilling units A and B for drilling these passages. As illustrated in Fig. 5, the drills 38 and 40 of the units A and B can be close together at the interfering point E, where further advance of the drill 40 would cause it to engage the drill 38 and thereby result in damage. This invention is particularly concerned with an arrangement whereby each drill unit can operate independently of the other down to the interfering point and thereafter the units are under such control that interference is prevented. The drilling units A and B are or can be identical. Each is constructed preferably as described in my above referred to application, and has mechanism for advancing the drill by successively increased distances into the work alternated with retracting movements to an intermediate retracted position where the drill clears the work and the chips can fall therefrom and terminated in a final retracting movement into a completely retracted position where the drill is held against further advance until restarted on a second cycle. The mechanism is also such that if undue pressure is caused to be exerted on the drill due to the dullness of the cutting edges or to the lodging of a chip under the drill the drill is repeatedly retracted and advanced from the bottom of the hole into the intermediate retracted position until the cause for the excess pressure has disappeared or until the mechanism is stopped by an operative. The mechanism for effecting this cycle of operations of the unit is not herein specifically illustrated as its specific construction is not necessary for an understanding of the present invention.

Each drill unit is mounted on a base 42 adapted to be secured in any desired position on the table 10. The base carries an electric motor 44 which through speed increasing gearing 46, see Fig. 4, 40 rotates a shaft 48 that has a telescoping connection with the drill spindle 50 rotatable in a head 52 slidable on a horizontal track 54 of the base 42. The drill 40 is thereby driven by the motor in any advanced or retracted position thereof. The base 54 is provided with a hydraulic cylinder 56 having a piston 58 therein which is connected by a piston rod 60 with the drill head 52 so that pressure applied alternately on opposite sides of the piston causes the drill head and the drill to reciprocate in opposite directions. The automatic advance and retraction of the drill into successively advanced positions in the work and the final movement of the drill into a fully retracted position is controlled by movements of the drill through a cam slide 62 that is secured to and is movable with the piston and the drill head. The cam slide 62 carries a cam 64 that has steps 66 and 68 thereon that are moved by movements of the cam slide into successive engagement with a pin 70 of a control lever 72 fixed to a vertical shaft 74 and having at its lower end an arm 76 that operates valve mechanism presently to be described. When the pin 70 and lever 72 are in the position illustrated in Fig. 4, the mechanism is set for rapid advance. When the pin 70 is on the horizontal ledge 78 between the two steps the mechanism is set for slow advance. Engagement of the step 68 with the pin 70 causes the lever 72 to be moved away from the engagement of the cam block into a reverse position illustrated by the dotted line, this movement being assisted by a spring pressed plunger 80. The hydraulic piston is then moved backwardly and a cam block 82 fixed to said cam slide 62 engages the pin 70 and moves it toward the cam

slide and into a neutral position midway between reverse and slow speed advance positions, where it is held until it is thrown into fast advance position either manually or under hydraulic control. The cam block 64 is at times locked to the cam slide by means not illustrated and is unlocked at times when the pin 70 is against the step 68 so that then the cam block is held stationary while the cam slide and the block advances. The amount of such movement determines the length 10 of the slow speed advance of the drill and is determined by means including a series of cam dogs 83, see Fig. 3, which are carried by the cam slide and successively engage mechanism, not shown, carried by the cam block 64, on successive advance movements of the drill, to advance the cam block with the cam slide to trip the control lever 72 and effect the reverse movement of the drill, the cam block 64 moving rearwardly with the slide. When the slide is in an intermediate retracted position determined by mechanism indicated generally at 85, Fig. 1 mechanism, not shown, is provided to move the control lever 72 inwardly into fast advance position whereupon the drill advances rapidly toward the work until the control lever is moved into slow advance position by the step 66 of the cam. During the final retracted position the cam block 64 is reset automatically to an initial position near the neutral cam 82 so that the mechanism is in condition to 30 repeat a second cycle of operations. Said cam block 64 thus constitutes accumulating stop means for progressively increasing the working stroke of the drill.

The mechanism is supplied with oil under pressure by means of a constantly operating pump 84 which receives oil from a sump or reservoir 86 and delivers pressure oil to the cylinder 88 of a compressed air accumulator 90 which is arranged to maintain a constant pressure of oil on the 40 system regardless of the number of drilling units that may be operating. Pressure oil is conducted from the accumulator through a pressure main or duct 92 through an interference valve casing 94, concerning which more will be said later, and 45 thence through a pipe or duct 96 to the inlet port 98 of a valve cylinder 100. Said valve cylinder has an exit port 102 adjacent the inlet port, which exit port is connected through a duct 104 with the inlet duct 106 of a speed controlling 50 valve cylinder 108. Said cylinder has an exit duct 110 adjacent the inlet duct which is connected through a duct 112 with the rear end of the hydraulic cylinder 56 and admits pressure fluid into the cylinder behind the piston in a direction to 55 effect the advance of the drill. The ends of the valve cylinder 100 are connected to exhaust ducts 114 which conduct exhaust oil back to the reservoir 86. The front end of the hydraulic cylinder 56 is connected to a duct 116 which is open into 60 the valve cylinder 100 between the pressure duct 96 and the right hand exhaust duct 114 and at times receives pressure liquid to act on the front end of the piston 58 in a direction to effect the retraction of the drill. The valve cylinder 100 is provided with spaced piston valves 118 and 120 therein connected to a valve stem 122 that is connected to a frame 124 operated by the arm 76 of the control lever 72. In the position of the piston valves illustrated pressure oil can flow 70 from the pressure duct 96 through the valve cylinder into the pipe 104, thence through the speed controlling cylinder 108 and thence into the rear end of the cylinder 56 to effect the rapid advance of the drill. Oil in the cylinder 56 in 75

front of the piston is exhausted freely through the duct 116 into the right hand end of the valve cylinder 100 where it flows through the duct 114 into the reservoir 86. When the pin 70 of the control lever 72 is on the ledge 78 of the cam block 64 the piston valves 118 and 120 are so set that the piston 118 partially closes the exit duct 102 while the piston 120 completely closes the outlet of the duct 116 into the valve cylinder. The only escape of the back pressure oil from the operating cylinder 56 through the duct 116 is through a branch duct 126 controlled by a valve 128 which imposes considerable resistance to the flow of the oil. Under these conditions the inflow of oil to the operating cylinder 56 is partially throttled and, due to the restricted escape of oil to the forward side of the operating cylinder, a back pressure of oil is set up which opposes the free advance of the operating piston 20 and hence gives a slow advance of the drill and also holds the drill against longitudinal vibration. The speed controlling cylinder 108 is provided with a piston valve 130 that controls the inlet port 106 and is urged by a spring 132 in a direction to clear the port and by back pressure oil from the operating cylinder 56 in the opposite direction to obstruct the inlet port. The resultant position assumed by the piston 130 is thus dependent upon the back pressure of oil in the operating cylinder and hence operates to maintain a constant rate of slow advance of the drill regardless of variations of resistance offered by the work to such advance. When the control lever 72 is in reverse position the piston 108 is 30 interposed between the inlet and outlet ports of the cylinder 100 and the piston 120 is located to the right of the opening of the duct 116 to said cylinder. In this position of the valve high pressure oil from the duct 96 flows through the duct 116 into the front end of the operating cylinder thereby moving it rapidly toward retracted position, the oil in the cylinder in the rear of the piston flowing freely through the duct 112 and through the valve casing 108 and 100 into the 40 left hand exhaust duct 114. The automatic operation of the mechanism can be interrupted and the unit moved into fully retracted position by means of a manually or otherwise operated three-way valve 134 which receives pressure oil from the pressure main 92 and is movable from a neutral position in oppositely disposed positions where it can direct pressure oil to flow through ducts 136 and 138 to the opposite ends of a cylinder 140 and act in opposite directions on the pistons 142 and 144 therein. The action of pressure oil on the piston 142 is to move it toward the right into engagement with a projection 146 of the frame 124 and to move said frame and the valve associated therewith into a reverse position, thereby effecting the reverse movement of the drill unit into a fully retracted position. The action of the pressure oil in the piston 144 is to move said piston and the frame 124 toward the left into a fast advance position of the valve to thereby initiate the cycle of operation of the drill unit.

The hydraulic control mechanism as so far described is or can be duplicated in the mechanism associated with the drill unit A and need not be further described.

For the purpose of preventing interference between the drills of the two units each unit has associated with its hydraulic system and interference valve 94 previously referred to, which valve, when operated, isolates its unit from the fluid

pressure source and thus stops the drill from advancing. Associated with the interference valves is an interference-valve selector valve cylinder 148 which is common to both units A and B, and a separate interference-position valve cylinder 150 associated with each drill unit and arranged to be operated thereby when the drill unit moves into interfering position. Each interference valve cylinder 94 receives pressure fluid from the pressure main or duct 92 into the bottom thereof and has an outlet duct 152 which communicates with the pressure duct 96 leading to the control valves for its associated unit. A piston 154 is movable in said cylinder and is connected at its upper end with a larger operating piston 156 therefor and is adapted to receive pressure fluid against the upper end thereof through a duct 158 in communication with an outlet duct 160 of the selector valve cylinder 148. The arrangement of the valve 94 is such that the oil pressure acting on the bottom end of the piston 154 from the duct 92 tends to maintain the piston in elevated position above the outlet duct 152 whereby to allow oil to flow to its associated drilling unit. When, however, oil pressure is applied to the upper end of the larger operating cylinder 156 the total pressure on the piston in a closing direction is greater than that on the piston 154 in an opening direction and hence the piston 154 moves to the bottom of the cylinder and isolates the port 152 from the pressure source thereby preventing the operation of the hydraulic mechanism of the unit. The selector cylinder 148 has an exhaust port 162 which is disposed in the middle thereof or at the left of the outlet port 160 for the unit B and at the right of the outlet port 160 for the unit A and conducts exhaust oil to the oil reservoir or sump through a duct 163. Pistons 164, 166 and 168 are disposed in said cylinder in spaced and connected relation. The connected pistons are freely movable in opposite directions within the cylinder and are adapted to be moved into one end or the other end of the cylinder by one or the other of the interference-position valves 160 of the respective units and to remain in whichever position they may have been moved until moved in the opposite direction. Each interference-position valve cylinder 150 is provided with an outlet duct 172 in the middle thereof which communicates through a duct 174 with a separate end of the selector valve cylinder 148, the port of the valve of the unit B communicating with the right hand end of the cylinder and the corresponding port of the unit B communicating with the left hand end of the cylinder. Each interference-position valve cylinder has an upper exhaust duct 176 communicating through a duct 178 with the open oil reservoir 86. Pressure oil is constantly maintained in the bottom of the cylinder by a duct 180 which is connected with the pressure main 92. A piston valve comprising a pair of spaced pistons 182, 184 is disposed within said valve cylinder 150, the piston being connected by a valve stem 186 that extends upwardly above the top of the cylinder and is terminated close under or in engagement with a pin 188 located at one end of a lever 190 pivoted at its other end to the base 64 of the unit. The pin and lever are disposed beneath the movable head 52 of the unit and said head has a cam block 192 thereon and movable therewith which in a predetermined position of the head is adapted to ride over the pin 188 and depress said pin and its lever and consequently to depress the valve stem 186. The cam block 192 is capable of adjustment longitudinally of the head 52 and of 75.

being secured to said head in any adjusted position by simple means not necessary to describe and is adapted to be set in such position as to depress the valve stem 186 when the cutting end 5 of the drill arrives at the interfering point E, Fig. 5. When the valve stem is depressed the piston 182 is depressed into a position where it isolates the outlet port 172 from the exhaust port 176 and the piston 184 moves into a position where 10 the bottom of the cylinder is in communication with the outlet port 172 and hence establishes oil pressure in the duct 172. The operation of the interference-position valve of the unit B thus establishes oil pressure in the right hand end of the 15 selector valve cylinder 148. This oil pressure acts first on the intermediate piston 166 and thence on the piston 168 to move the three pistons as far as they can go into the left hand end of the cylinder. In this position the piston 168 will be disposed 20 between the right hand port 160 and the enlarged right hand end of the cylinder, the piston 166 will be disposed between the duct 162 and the left hand duct 160, and the piston 164 will be disposed in the enlarged left hand end of the cylinder. 25 Hence the operating piston 156 of the interference valve 94 of the unit B is isolated from fluid pressure and thus the piston 154 is maintained in elevated or open position so that the operation of the interference-position valve 150 30 of its associated unit B does not effect the operation of the hydraulic mechanism of the unit and the unit can continue to advance, assuming that the drill of the unit A has not yet advanced into interference-position. The above described operation places the interference-position valve 150 35 of the unit A in control of the operating piston 156 of the interference valve 94 of this unit. Hence when the unit A arrives at interference-position the cam of said unit operates its interference-position valve and places fluid pressure on the operating piston 156 through the duct 174 of said unit and the selector valve 148. The pressure on said operating piston overbalances the pressure on the smaller valve piston and causes it to close 40 thereby stopping the flow of pressure oil to the hydraulic operating cylinder of the unit and hence arresting the advance of the drill of its own unit A beyond interfering-position. When, however, the drill of unit B is retracted beyond interfering-position, the interference-position valve 45 thereof is released and the valve moves upwardly due to the oil pressure on the bottom thereof and thus exhausts the pressure in the right hand end of the selector valve cylinder through the ducts 174 and 176 of the unit B. The selector valve pistons are now unbalanced due to the high oil pressure now existing solely in the left hand end of the cylinder and hence the pressure moves the pistons to the right hand end of the cylinder 50 and into the position illustrated. In this position the pressure on the operating piston 156 of the interference valve of the unit A is exhausted through the exhaust duct 170 and hence the piston 154 of said interference valve is opened and 55 consequently the drill of unit A starts to advance from interference-position. If the drill of the unit B should be again advanced it will advance only so far as interference-position and will then be stopped in the manner above described. With 60 this arrangement the unit that arrives first in interference-position gains precedence over the other and continues to advance and holds the other stationary in interference-position. The unit that arrives at interference-position first 65 continues to advance until it is retracted auto-

matically by the control mechanism associated with the cam block 64 whereupon the other unit takes precedence and starts its advance from interference-position. A unit that has lost precedence by reasons of its retraction can again advance to interference-position providing its cycle of operations has not been completed and will remain stationary in interference-position until the retraction of the advancing unit, whereupon the stationary unit will advance. 10

I claim:

1. A drilling machine comprising the combination of two drilling units, independent hydraulic mechanism for advancing the drills of each unit simultaneously along convergent lines into a potential interfering position, and means responsive to the movements of said mechanisms for causing the mechanism that arrives first in interfering-position to continue to advance and to stop the advance of said other mechanism into interfering-position and means subsequently to advance said other mechanism but only after the first mechanism has been retracted from interfering-position. 15

2. A drilling machine comprising the combination of two drilling units, hydraulic mechanism associated with each unit for advancing and retracting the drill thereof independently of the other unit, a separate valve controlling the supply of pressure fluid to each of said hydraulic mechanisms, means operated by each unit when the drill thereof arrives in a predetermined position for closing the valve of said other unit and arresting the operation of said hydraulic mechanism thereof, and means for resuming the advance of the arrested mechanism following the retraction of the other mechanism. 25

3. A drilling machine comprising the combination of two drilling units, hydraulic mechanism for advancing and retracting the drill of each unit independently of the other unit, a valve associated with each unit for controlling the supply of pressure fluid to the hydraulic mechanism thereof, selector mechanism for operating said valves selectively having means operated in a selected 40 manner independently by each of said units when the drill thereof is in a predetermined position for arresting the operation of the hydraulic means of the other unit, and means for advancing the arrested unit following the retraction of the other 45 unit. 50

4. A drilling machine comprising the combination of two drilling units, hydraulic mechanism associated with each unit for advancing and retracting the drill thereof independently of the other unit, a valve associated with each unit for controlling the supply of pressure fluid to the hydraulic mechanism thereof, means including a selector valve movable into alternate positions for effecting the alternate closure of said control 60 valves, means including valves associated with said drilling units and arranged to be operated thereby when the drills of said units are in predetermined positions for effecting the operation of said selector valve to close the control valve associated with the other unit and arrest the advance thereof, and means for re-advancing the arrested unit following the retraction of the other unit. 65

5. A drilling machine comprising the combination of two drilling units each having hydraulic mechanism for advancing and retracting the drill of its unit independently of the other unit, a control valve associated with each unit for controlling the supply of pressure fluid to the hydraulic mechanism thereof, selector mechanism controlling 70

- the operation of said valves, means including valves each associated with the separate one of said two units and operated thereby in a predetermined position of the drill thereof for effecting 5 the operation of said selector mechanism to arrest the operation of the hydraulic mechanism of the other unit, and means for readvancing the arrested unit following the retraction of the other unit from interference position.
- 10 6. A drilling machine comprising the combination of two drilling units arranged at an angle to each other, hydraulic mechanisms each associated with a separate unit for advancing the drills thereof along convergent lines to an interfering- 15 position, interference valves each associated with a separate hydraulic mechanism for controlling the supply of pressure fluid thereto, means associated with each drilling unit and operated thereby when the drill of said unit is in interfering- 20 position for operating the interference valve of the other unit to disable the operation of the hydraulic mechanism thereof, and means for readvancing the arrested unit following the retraction of the other unit from interference position.
- 25 7. A drilling machine comprising the combination of two drilling units arranged at an angle, hydraulic mechanism separately associated with said units for advancing the drills thereof along convergent lines to an interfering-position, control valves separately associated with said hydraulic mechanisms for controlling the supply of pressure fluid thereto, selector mechanism for selectively operating said control valves, and means separately associated with each drilling 30 unit and operated thereby in the interfering-position of the drill thereof for operating said selector mechanism to effect the operation of the control valve for the other unit to prevent the advance of said hydraulic mechanism.
- 35 8. A drilling machine comprising the combination of two drilling units each having a hydraulic mechanism associated therewith for advancing and retracting the drill of said unit independently of the other unit, a valve associated with each 40 hydraulic mechanism for controlling the supply of pressure fluid thereto, a second valve separately associated with each unit and operated thereby when the drill of said unit is in a predetermined position, means associated with said second valves for operating the control valve of the unit associated with an unoperated second valve for preventing the advance of the hydraulic mechanism thereof, and means for advancing the arrested unit following the retraction of the other unit 45 from interference position.
- 50 9. A drilling machine comprising the combination of two drilling units each having a movable head that supports the drill, hydraulic mechanism for advancing and retracting said head, and means including valve mechanism for automatically retracting and advancing said head, a source of fluid pressure, means including a normally opened control valve connecting each hydraulic mechanism separately with said source of fluid pressure, and means including a valve associated with each drilling unit and operated by said head in a predetermined position thereof for effecting the closing of the control valve of the other unit and the disabling of said hydraulic mechanism.
- 55 10. A drilling machine comprising the combination of two drilling units each having a movable drill carrying head, hydraulic mechanism for advancing and retracting said head, and means including valve mechanism for automatically effecting the retraction and advance of said head,
- a source of fluid pressure, means including a control valve separately connecting said source of fluid pressure with each of said hydraulic mechanisms, means including selector mechanism operated independently by each head when it is 5 in a predetermined position for operating the control valve of the other unit and for arresting the operation of said mechanism, and means responsive to the retraction of one unit from interference position for freeing the arrested unit for 10 operation.
11. A drilling machine comprising the combination of two drilling units each having drill carrying heads that are movable along convergent lines to advance the drills into an interfering- 15 position, hydraulic operating mechanism for independently advancing and retracting each head, means including valve mechanism controlled by the movements of each head for advancing and retracting said hydraulic mechanism, a source 20 of fluid pressure, means including interference valves separately connecting said source with said hydraulic mechanisms, selector valve mechanism associated with both drilling units for operating said interference valves, and a separate interference-position valve associated with each of said units and operated thereby when the drill thereof is in an interfering-position for operating said selector mechanism in a manner to effect the operation of the interference valve 25 for the other unit whereby to disable the hydraulic mechanism thereof.
12. A drilling machine comprising the combination of two drilling units, each having drill 30 operating mechanism and hydraulic mechanism for advancing and retracting the drills, a source of fluid pressure, means including a control valve for said hydraulic mechanisms separately connecting said source with said hydraulic mechanisms, hydraulic means for operating said control valves, a selector valve for operating said hydraulic means comprising a valve piston, and means operated by each of said units when the drill thereof is in a predetermined position for 35 applying hydraulic pressure in opposite directions to said piston to cause it to move into a position to admit fluid pressure to the hydraulic means of the control valve of the other unit to arrest the operation of the hydraulic mechanism thereof.
- 40 13. A machine tool including independent hydraulic devices to advance a plurality of cutters simultaneously and independently along convergent lines into a potential cutter-interference position, means providing hydraulic circuits for said devices, and interference-preventing means including valve mechanisms controlling said circuits responsive to the advance of one cutter into said cutter-interference position to de-energize the hydraulic advancing devices of all other 45 cutters and to continue the advance of said one cutter.
- 50 14. A machine tool including a pair of cutter operating mechanism, hydraulic devices each associated with a separate operating mechanism to 55 advance their respective cutters simultaneously and independently along convergent lines into a potential cutter-interference position, means providing hydraulic circuits for said devices, and interference-preventing means including valve mechanisms controlling said circuits responsive to the advance of one mechanism into said interference position to disable the hydraulic device and to arrest the advancing movement of the other cutter advancing mechanism and to con- 60
- 65 70 75

tinue the advance of said one advancing mechanism.

15. A machine tool comprising the combination of two cutter operating units, hydraulic devices each associated with a separate unit to advance their cutters simultaneously and independently along convergent lines into a potential cutter-interference position, means providing hydraulic circuits for said devices, and interference-preventing means including valve mechanisms controlling said circuits and controlled by the movements of any of said cutter advancing means to permit the continued operation of the associated hydraulic device to advance its cutter into interference position and to de-energize the circuit of the other hydraulic device and to arrest the advancing movement thereof with its associated cutter out of interference position.

16. A machine tool including a pair of cutter operating mechanisms, hydraulic devices each associated with a separate mechanism having means to advance their respective cutters simultaneously and independently along convergent lines to a potential cutter-interfering position, means providing hydraulic circuits for said devices, and interference-preventing means including valve mechanisms controlling said circuits and governed by the position of said mechanisms to effect the operation of one hydraulic device to advance its associated cutter into interfering position and to de-energize the hydraulic device of the other unit to prevent advance of its cutter into interfering position.

17. A machine tool including two cutter operating mechanisms, independent hydraulic devices to advance the cutters of said mechanisms simultaneously and independently along convergent lines to a potential cutter-interfering position, means providing hydraulic circuits for said devices, and interference-preventing means including valve mechanisms controlling said circuits and operated by the hydraulic device of that cutter that advances first into interfering position to arrest the advancing movement of the hydraulic device of the other unit.

18. A machine tool comprising the combination of two cutter operating mechanisms, independent hydraulic devices for advancing the cutters of said mechanisms simultaneously and independently along convergent lines to a potential cutter-interfering position, means providing hydraulic circuits for said devices, and interference-preventing means including valve mechanisms controlling said circuits and operated by the hydraulic device of whichever cutter arrives first in interfering position to effect the continued advance of the associated cutter and the halting of the advancing movement of the hydraulic device of the other cutter.

19. A drilling machine comprising the combination of two drilling units, independent hydraulic devices for advancing the drills of each unit simultaneously and independently along convergent lines into a potential drill-interfering position, means providing hydraulic circuits for said devices, interference-preventing means including valve mechanisms in control of said circuits and responsive to the movement of said devices for causing the device that arrives first in a position corresponding to said drill-interfering position to continue to advance and to stop the advance of said other device into interfering-position and means responsive to the retraction of said first device to effect the advance of said other device.

20. A drilling machine comprising the combination of two drilling units movable along convergent lines into a potential interference-position, independent hydraulic devices for advancing and retracting the drills of said units, said devices being simultaneously operative, a source of fluid pressure for operating said hydraulic devices, valves controlling the connection of said source of fluid pressure with each hydraulic device, and means operated by any one unit when the drill thereof is in a potential interference position for closing the valve of the other unit and arresting the operation of the hydraulic device thereof with the associated unit thereof out of interference position, whereby to prevent interference of the drills.

21. A drilling machine comprising two drill holders movable toward each other into a potential drill interference position, hydraulic devices for reciprocating said holders, hydraulic circuits for said devices, means including advancing valve mechanisms controlling said circuits and normally responsive to different positions of said holders to advance said holders independently of each other and simultaneously toward each other by a series of reciprocating movements through said drill-interference position, and interference-preventing means including interference-valve mechanisms controlling said hydraulic circuit and responsive to the positioning of any holder in said drill-interference position to disable the hydraulic circuit of the hydraulic devices of the other holder and to halt the advance of said other holder at such interference-position, said interference preventing means also being responsive to the retraction of said one holder from interference position to effect the advance of said other holder into interference position.

22. In a step drilling machine, the combination of two tool members movable toward each other into a potential tool-interference position, a hydraulic device associated with each tool member for moving it independently of the other, each hydraulic device including a cylinder, a piston connected to and movable with its associated tool member, a hydraulic circuit including means for delivering fluid to and receiving fluid from the opposite ends of each of said cylinders to cause reciprocation of the associated tool relative to the work, means movable in unison with each of said pistons and cooperating with a plurality of valve units for moving each of said pistons and the associated tool independently of and simultaneously with the other piston and its associated tool in a series of progressively advancing reciprocating strokes in cycles, each cycle comprising a rapid traverse movement toward the work, a relatively slow feed rate movement through a portion of the work at a rapid traverse movement from the work, accumulating stop means separately associated with each tool holder and responsive to the feed movement in each cycle of its tool holder for progressively increasing the depth of rapid traverse in the succeeding cycle thereby advancing the feed range, and interference-preventing means including valve mechanisms controlling said hydraulic circuits and responsive to the movement of whichever one of the tool members it is that first advances into tool-interference position to permit that tool member to continue its cycle and to stop the other tool member from movement through tool-interference position.
